UNITED STATES PATENT OFFICE.

ADRIAN ROY SOLOMON, OF SAN FRANCISCO, CALIFORNIA.

DESIGN FOR A LAMP CANOPY.

Application filed August 31, 1927. Serial No. 23,258. Term of patent 7 years.

To all whom it may concern:

Be it known that I, ADRIAN ROY SOLOMON, a citizen of the United States, residing at San Francisco, county of San Francisco, and State of California, have invented a new, original, and ornamental Design for a Lamp Canopy, of which the following is a specification, reference being had to the accompanying drawing, forming part thereof, wherein the figure is a perspective view of my ornamental design for a lamp canopy.

I claim:

The ornamental design for a lamp canopy, as shown.

ADRIAN ROY SOLOMON.
